UNITED STATES PATENT OFFICE.

JAMES C. JOHNSTON, OF BLACKWELL, OKLAHOMA.

FLYING-MACHINE.

1,068,663.

Specification of Letters Patent.

Patented July 29, 1913.

Application filed April 18, 1910. Serial No. 556,008.

To all whom it may concern:

Be it known that I, JAMES C. JOHNSTON, a citizen of the United States, residing at Blackwell, in the county of Kay and State 5 of Oklahoma, have invented a new and useful Flying-Machine, of which the following is a specification.

This invention relates to flying machines and more particularly to means whereby 10 the equilibrium of a machine may be maintained automatically.

One of the objects of the invention is to provide a plurality of controlling planes all of which are under the control of a pendulum, whereby, when the machine moves 15 out of horizontal position and the sustaining action of the aeroplane is thus reduced the controlling planes will be shifted so as to present their broad faces to the air in 20 the path thereof and thus operate to deflect the machine until it has reassumed its proper position.

A further object is to provide means whereby both the lateral and longitudinal 25 stability of the machine may be maintained by the operation of the same pendulum, there being both side, front and rear controlling planes connected to and movable with the pendulum.

30 A still further object is to provide means whereby the pendulum may be shifted manually for the purpose of controlling the flight of the machine.

With these and other objects in view the 35 invention consists of certain novel details of construction and combinations of parts hereinafter more fully described and pointed out in the claim.

In the accompanying drawings the preferred form of the invention has been shown.

In said drawings: Figure 1 is a plan view of a portion of a flying machine structure having the present improvements applied 45 thereto. Fig. 2 is a section on line A—B of Fig. 1. Fig. 3 is a side elevation of the machine. Fig. 4 is an enlarged perspective view of the pendulum and the adjoining portion of the mechanism. Fig. 5 is a plan 50 view of one of the controlling planes.

Referring to the figures by characters of reference 1 designates a frame which can be of any suitable construction, this frame varying according to the type of machine to 55 which the improvements are applied. The frame may form part of any of the various

types of flying machines, such as a monoplane, biplane, and triplane, and can even be a portion of the car of a dirigible balloon or the like. In the type of machine shown 60 in the drawings, a propeller is located at the front end of the machine and a rudder at the rear end thereof.

Mounted within the front and rear portions of the frame 1 are controlling planes 2 each of which is provided with a centrally disposed pivot rod 3 extending longitudinally thereof and mounted at its ends within the side portions of the frame. Parallel base strips 4 may be secured upon each 70 of the planes 2 and each of these strips is preferably formed with a series of apertures 5. Eye bolts 6 or the like are preferably detachably mounted within one of the apertures 5 in each strip 4 and a V-shaped 75 link 7 is pivotally connected to the eye bolts and also to the apex of a triangular lever 8 carried by the structure 1. The connections between the link 7 and the controlling plane 2 are located adjacent the rear edge 80 of said plane. The rear controlling plane is similar to the front plane and has similar connections.

The side controlling planes are of the same construction as the front and rear 85 planes 2 and each of these planes, which has been indicated at 9, has a central trunnion 10 at each end journaled within the structure 1. A lever 11, similar to the levers 8, is fulcrumed upon the structure 1 at a point 90 above each of the planes 9 and is connected by means of a link 12 to the front edge portion of the plane 9, the said link being pivotally connected to the plane 9 in the same manner as are the links 7. The levers 11, 95 however instead of extending in the direction of the length of the structure 1 are extended transversely thereof.

A weighted controlling lever or pendulum 13 is suspended within the structure 1 100 at the center of gravity. Cords 14 extend in opposite directions from the upper end of the pendulum and are attached to the upper and lower portions respectively of the two levers 8 and additional cords 15 extend laterally from the upper portion of the pendulum 14 and are connected to the upper ends of the levers 11. The lower ends of these levers 11 are connected by cords 16 to the pendulum at a point below 110 the pivot thereof and cords 17 extend from the same point on the pendulum and to the

levers 8 as shown particularly in Fig. 3, the forwardly extending cords 17 crossing the adjoining cord 14.

The pivot of the pendulum is formed of 5 trunnions 18 mounted in the wall of an opening 19 formed in a cross strip 20, the said trunnions extending transversely of the strip. Additional trunnions 21 extend from the ends of the strip and are mounted 10 in suitable supports 22. It will thus be seen that the pendulum is free to swing in any direction but cannot rotate.

It is to be understood that the pendulum 15 constantly hangs vertically within the frame 1 and that when the machine is properly balanced while in flight, the planes 2 and 9 lie in substantially the same plane. Should the machine tilt laterally, the sustaining planes would be correspondingly tilted thus 20 causing the machine, under ordinary conditions, to plunge downwardly at one side. By the provision of the balancing mechanism which has been disclosed, however, this 25 plunging action is prevented because the pendulum, by remaining vertical during the tilting of the machine, causes the levers 11 to work on their fulcrums and to simultaneously shift the controlling planes 9 in opposite directions, the lower face of the lower 30 plane 9 and the upper face of the upper plane 9 being presented to the air in the path thereof so that during the continued forward flight of the machine, the pressure 35 of the air against these inclined faces will be such as to restore the machine to its proper angle.

Should the machine plunge either forwardly or backwardly the pendulum will 40 swing toward the rear or front of the machine and motion will be transmitted therefrom through the cords 14 and 17 to the front and rear controlling planes 2 which will be tilted so as to lie in intersecting planes, and thus coöperate with the air in 45 the path thereof to shift the two ends of the machine in opposite directions and return the machine to its proper angle of incidence.

In order that the machine may be manually guided vertically and tilted laterally 50 so as to meet varying atmospheric conditions, mechanism is provided whereby the pendulum 13 can be shifted out of its vertical position in order to produce the desired actuation of the controlling planes connected to it. This mechanism preferably consists of a lever 23 having a fork 24 straddling and pivoted on the strip 20. A rod 55 is connected by universal joints 26 to the lever and to the pendulum.

By means of the mechanism which has 60 been described the pendulum 13 can be shifted laterally by swinging the lever 23 so as to cause the rod 25 to pull or push the pendulum. Obviously such movement of 65 the pendulum will result in the actuation of

the side controlling planes 9, motion being transmitted to them through the cords 15 and 16. Should it be desired to shift the pendulum 13 so as to actuate the controlling planes 2, the lever 23 is shifted so as 70 to swing the strip 20 upon its longitudinal axis. Motion is thus transmitted through the trunnions 18 to the pendulum 13. The cords 14 and 17 therefore operate to swing the planes 2 about their pivots. The actuating mechanism which has been shown in detail in Fig. 4 is of such a character as to offer practically no resistance to the automatic operation of the pendulum 13, it being understood that the various parts of said 80 operating mechanism are very light and that ball bearings may be employed to reduce friction to the minimum.

As has heretofore been pointed out the balancing or controlling planes can be used 85 in connection with various types of machines. Where they are employed in connection with monoplanes, it is desirable to locate them below the said planes and, when they are used in connection with bi-planes, 90 it is preferred to locate them between the upper and lower planes. While this balancing mechanism is particularly useful in connection with aerodromes or heavier than air machines it is to be understood that they 95 can also be employed in connection with the cars of dirigible balloons and other lighter than air machines.

Various changes can of course be made in the construction and arrangement of the 100 parts without departing from the spirit or sacrificing any of the advantages of the invention as defined in the appended claim.

What is claimed is:—

A flying machine including a frame, 105 front, rear and side controlling planes mounted to swing about axes extending transversely of the line of flight, levers supported above said planes, link connections between the levers and the rear portions of 110 the planes thereunder, a longitudinally extending strip mounted within the frame and adapted to swing about an axis extending transversely of the line of flight, a lever straddling and pivotally connected to said 115 strip for swinging the strip about its axis, a pendulum extending through the slot in the strip and adapted to swing relative to the strip in a plane extending transversely of the line of flight and adapted to swing 120 with said strip in a plane parallel with the line of flight, a rod connected, by universal joints, to the pendulum and to the lever which is connected to the cross strip, connections between the upper end of the pendulum and the levers above the controlling planes for actuating said planes in one direction when the pendulum is swung, and connections between said levers and that portion of the pendulum below the slotted 125 130

cross strip for actuating the controlling planes in the opposite direction during the movement of the pendulum, said pendulum being located between the side controlling planes and also between the front and rear controlling planes.

In testimony that I claim the foregoing

as my own, I have hereto affixed my signature in the presence of two witnesses.

JAMES C. JOHNSTON.
